SHOE MANUFACTURING MACHINERY

Daniel Colburn, Rolla, Mo., assignor to Johnson-
Stephens & Shinkle Shoe Company, St. Louis,
Mo., a corporation of Missouri

Application August 1, 1935, Serial No. 34,128

3 Claims. (Cl. 198—131)

The invention relates to the manufacture of shoes and more particularly to the handling of a series of shoe parts, such as soles, immediately following an operation on one machine, such as 5 the applying of cement, at which time the parts should be kept spaced from other parts.

The object of the invention is to facilitate the handling of shoe parts by simplifying the actions of the operator in transferring the shoe part to 10 a rack whereby the operator can better concentrate on the operation of the machine.

More specifically, the invention comprises the provision of a rack for holding successive shoe parts placed adjacent to the work receiving portion 15 of the machine and movable along with the operation of the machine to continually present an empty shoe receiving member at the same point.

In the accompanying drawing illustrating a 20 selective embodiment of the invention—

Figure 1 is a front elevation of a machine for applying cement to shoe soles and a movable rack associated therewith together with mechanism for operating the machine and the rack simultaneously.

Figure 2 is an enlarged detail of a portion of the rack and its moving mechanism and is taken approximately on the line 2—2 of Figure 1.

Figure 3 is a detail horizontal section taken on 30 the line 3—3 of Figure 1.

Figure 4 is a view of a shoe sole or insole upon which the machine operates and which is to be stored temporarily in the rack.

The cement applying machine includes a stand- 35 ard 1 supporting a casing 2 for housing and providing bearings for gearing which drives a series of rollers 3. Adjacent to rollers 3 is a discharge nozzle 4 of a cement feed device including a conduit 5, a pressure gauge 6, and a control lever 7. The roller mechanism is driven by the belt 8 40 leading from a speed reducer 9 operated by motor 10. At the left of the machine is an elongated vertical angular framing 11 providing vertically spaced bearings 12 for the shafts for sprockets 13 45 which mount an endless chain 14. The rack R comprises a pair of side members 15, upper and lower cross members 16, and a plurality of wire V's 17 having their ends seated in side members 15 and projecting outwardly therefrom to form a 50 series of shelf members, one above the other, each adapted to receive one of the shoe soles S.

The upper cross member 16 of the rack has a hook 16^a whereby the rack may be readily attached to or removed from any link of the chain 55 14. Framing angles 11 form tracks for receiving

and guiding side members 15 of the rack as the latter moves with chain 14.

Shafting 18, a speed reducer 19, and belt 20 serve to drive the lower sprocket 13 from the same mechanism which operates the cementing machine rollers, and the entire assembly is so constructed that rack R will move upwardly at a speed which will make it possible for the operator to remove a sole from rollers 3 and insert it in a shelf 17 without reaching upwardly or downwardly an undue distance from the level of the rollers. In other words, as the upper shelves 11 are filled, the rack is moved upwardly so as to bring lower shelves into the height zone most convenient for the deposit of soles upon the rack by 15 the operator.

An electric switch, as indicated at 21, includes a trigger 22 extending into the path of the rack and when the rack has reached a predetermined height it will engage trigger 22 to operate switch 21 to open the circuit of the driving motor and, if desired, to sound a warning which will direct the attention of the operator or an attendant to the fact that the loaded rack should be removed from the framing and chain and an empty rack 25 substituted therefor.

The device is simple and economical in construction and provides a substantial convenience for the operator who can dispose of cemented soles more readily and with less likelihood of smearing cement on the smooth portions of other soles than if he had to deposit each sole at a different level than the one before.

Obviously the device is not limited to the handling of shoe soles following a cement operation 35 but, with suitable modifications, may be adapted for use in connection with other shoe manufacturing operations.

It is not necessary for the rack elevating mechanism to be operated by the cement roll drive. Separate motor and shafting may be provided for this purpose. The drive arrangement and other details of the structure shown are relatively unimportant and may be varied substantially without departing from the spirit of the invention and the exclusive use of all those modifications coming within the scope of the claims is contemplated.

I claim:

1. In combination, an endless chain, means for moving said chain vertically, and a rigid rack having a hook element for readily engaging or disengaging any of the links of said chain to hang said rack thereon, said rack including spaced side 50

bars and wire supports carried thereby converging towards each other forwardly from said bars, and rigid upright angle irons spaced apart at the sides of said chain with flanges extending forwardly of said chain to engage said bars laterally and with their other flanges extending towards each other to engage said bars rearwardly, said angles guiding and steadyng said rack as it moves with said chain.

10 2. In combination, an endless flexible traveler moving in a given plane, rigid tracks in said plane at opposite sides of said traveler and extending lengthwise thereof, an elongated rack having spaced sides disposed to slide on said tracks and 15 including means for readily attaching and detaching the rack to and from said traveler, there being interengaging guiding elements on said rack and tracks, said rack having a series of spaced shelf-like members projecting outwardly from

said sides and said tracks to individually receive successive parts delivered to the rack.

3. A device for receiving in succession from cementing machine a plurality of shoe soles having adhesive cement applied to one face thereof comprising an endless flexible traveler having movement generally in an upright plane, rigid tracks of angular cross section in said plane a opposite sides of said traveler and extending lengthwise thereof, an elongated rigid rack having spaced sides disposed to slide in the angles of said tracks and including means for readily attaching and detaching the rack to and from said traveler, said rack having a series of closely spaced sole supporting elements projecting forwardly from said sides and said tracks to receive successive soles edgewise and individually support them.

DANIEL COLBURN.
